UNITED STATES PATENT OFFICE.

HENRY W. L. FOX, OF BOSTON, MASSACHUSETTS.

LUBRICATING DEVICE.

1,165,402.

Specification of Letters Patent.

Patented Dec. 28, 1915.

Application filed December 8, 1914. Serial No. 876,072.

To all whom it may concern:

Be it known that I, HENRY W. L. Fox, a citizen of the United States, residing at Boston, county of Suffolk, Commonwealth of Massachusetts, have invented certain new and useful Improvements in Lubricating Devices, of which the following is a specification.

This invention relates to lubricating devices and particularly to a friction-applied lubricating device.

My invention is especially designed for use in connection with a vibratory body wherein the application of the lubricant is dependent upon the vibrations of the body itself. In this way I secure an application of the lubricant only when the body is in use, that is, when it is vibrating, and therefore prevent a needless lubricating of the body when it is not in use. This is effected in the present invention by the use of a saturable seal member for the feed opening of a lubricant container in combination with a vibratory body against which the seal bears. The vibrations of the body to be lubricated act to compress the saturated sealing member on its seat, thus effecting a transfer of the lubricant to the vibratory body along which it travels to all parts thereof by capillary attraction.

My invention is obviously capable of use with numerous vibratory bodies, but for the purposes of the patent I have shown it in its application to the shock absorption springs of an automobile where it is especially useful. It should be understood, however, that this is simply an illustrative embodiment of the principles of my invention and is not intended to limit the device to this use.

The construction and operation of my invention will be more fully disclosed in the specification which follows.

In the drawings forming a part of that specification I have shown a lubricator which not only clearly illustrates the principles involved but is in itself a form found satisfactory in use.

Throughout specification and drawings, like reference numerals are correspondingly applied, and in these drawings: Figure 1 is an elevation of a lubricator in accordance with my invention showing its application to the shock absorption springs of an automobile, the springs being shown in section, and Fig. 2 is a plan view thereof.

The device of my present invention consists essentially of a clamping member having a lubricant container and a saturable sealing member for the delivery opening of said container disposed in contact with the vibratory body to be lubricated. In the form of my invention selected as an illustrative embodiment I have shown the clamping member as consisting of a single casting having a gravity feed oil well cored therein and the saturable member as a simple pad loosely seated over the delivery opening of the oil well and in contact with the leaves of an automobile spring held in said clamp.

I have indicated at 1 the horizontal base of the clamp upon which are seated the superimposed leaves 2 of a spring which is clamped therein by one or more screws 3 set up in a lateral flange 4 formed on one edge of the base 1. The opposite edge of the base 1 extends as a vertical wall 5 terminating in a horizontal wall 6 partially overlying the base 1.

The vertical wall 5 has a gravity feed oil well 7 cored therein. The oil well 7 has a lateral delivery opening 8 through the wall 5 and preferably centrally thereof. The filling opening of the oil well is closed by a pivoted swing cover 9.

The delivery opening 8 of the oil well is closed by a seal 10 compressibly held against an internal rib 11 and a shoulder 12 formed on the wall 5 adjacent the portions 1 and 6 by the leaves of the spring. The seal is preferably of a size to wholly cover the inner face of the wall 5 with its upper edge bearing against the bottom face of the overhanging wall 6. The seal is of a readily saturable compressible material which acts as a swab to apply the lubricant to the leaves of the spring under the compressive action thereof due to their vibration. I find felt or similar absorbent and compressible material well adapted for this purpose, although obviously any compressible material through which the oil can readily permeate may be used. The rib 11 and shoulder 12 assist in holding the pad 10 to its seat over the opening 8.

In use, the leaves of the springs are clamped within the holder with the lowermost leaf held under the rib 11 by the set screws 3. The leaves press the seal 10 tightly to its seat over the delivery opening of the oil well. The oil feeds by grav-

ity and thoroughly saturates the seal. As the leaves of the spring are vibrated the pad is compressed and the lubricant absorbed thereby is forced out onto those parts of the leaves in contact with the pad and is transferred by capillary attraction to all parts of the leaves. The spring is therefore not only self lubricating but is lubricated only when it is in use, thus effecting a saving in the lubricant and at the same time maintaining the springs sufficiently lubricated. The pad acts as a seal for the oil well as well as a transfer medium for applying the lubricant to a relatively large part of the leaves.

15 The device of my present invention may obviously be used with a large range of vibratory bodies and the lubricant container does not necessarily need to be an integral part of the clamp.

20 These and various other modifications in the form and construction of my device may obviously be resorted to within the limits of the appended claims.

What I therefore claim and desire to secure by Letters Patent is—

1. A lubricator for a multi-ply leaf spring comprising a reservoir having a transverse delivery area adapted to overlap the interstices between the plies of said spring and a clamp disposed for engagement with one ply only.
2. A lubricator for a multi-ply leaf spring comprising a reservoir having a transverse delivery area adapted to overlap the interstices between the plies of said spring and a clamp disposed for engagement with one ply only whereby said leaves are left free to move relatively to each other.
3. In a lubricating device of the class described, a clamp comprising a base having a lateral flange at one edge and a wall at its opposite edge, a lubricant container associated with said wall and having a delivery opening through said wall, a saturable sealing member for said delivery opening having a seat against said wall, a vibratory body to be lubricated in compressive contact with said sealing member, and means in said lateral flange engaging said body.
4. In a lubricating device of the class described, a clamp comprising a base having a wall at one edge, a lubricant container cored in said wall and having a delivery opening through said wall, a saturable sealing member for said delivery opening having a seat against said wall, a vibratory body to

be lubricated in compressive contact with said sealing member, and a rib on said wall near said base under which said vibratory body is engaged.

5. A lubricator for a multi-ply leaf spring comprising a support, a permeable pad on said support and disposed to overlap the interstices between the plies of said spring, and a reservoir having a delivery to said pad, and a clamp disposed for engagement with one ply only.

6. A lubricator for a multi-ply leaf spring comprising a reservoir having a transverse delivery area adapted to overlap the interstices between the plies of said spring and a support having engagement with one ply only whereby said plies are left free to move relatively to each other.

7. A device for use with a multi-ply leaf spring, comprising a member having such engagement with said plies as to permit free movement thereof relative to each other, and means influenced by the movement of said plies for distributing a lubricant between the interstices of said plies.

8. A device for use with a multi-ply leaf spring, comprising a reservoir for a lubricant having a delivery to the spring, a transfer element effectively disposed relative to said delivery and in lubricant distributing relation to the interstices between said plies, and a clamp permitting free movement of the plies relative to each other to compress said pad and effect a distribution of the lubricant content thereof.

9. A device for use with a multi-ply leaf spring comprising a support having engagement with one ply only and permitting free relative movement of said plies, and a reservoir for a lubricant having a delivery area to all of said plies.

10. A device for use with a multi-ply leaf spring comprising a support having an engagement with said spring permitting free relative movement of the plies thereof, a reservoir for a lubricant having a delivery and a transfer element effectively disposed relative to said delivery and in surface contact with said plies.

In testimony whereof I affix my signature in presence of two witnesses.

HENRY W. L. FOX.
